UNITED STATES PATENT OFFICE.

ALONZO HALLIN PENCE AND WILLIAM ALONZO PENCE, OF SOMERVILLE, ALABAMA.

MECHANICALLY-OPERATED FIGURE TOY.

Application filed August 3, 1925. Serial No. 47,964.

This invention relates to mechanically operated figure toys designed primarily for use as signs for advertising purposes, one of the objects being to provide means operated by air currents whereby the attention of the observer will be attracted.

A further object is to provide a sign utilizing a jointed or movable figure simulating an animal and which figure will be actuated by air currents.

Another object is to provide mechanism which is simple in construction, will not readily get out of order, and which will operate freely.

15 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

20 In the accompanying drawings the preferred form of the invention has been shown.

In said drawings,

Figure 1 is a side elevation, certain of the parts being broken away.

30 Figure 2 is a vertical longitudinal section through the figure portion of the sign, the same being shown in normal position.

Figure 3 is a section on line 3-3 Figure 1.

35 Referring to the figures by characters of reference 1 designates a pedestal in which a stem 2 is mounted to rotate freely, this stem being connected to and extended downwardly from a frame 3.

40 Journaled within the frame is a shaft 4 provided at its front end with a wind wheel 5. Secured to this shaft is a gear 6 adapted to drive a larger gear 7 secured to another shaft 8 which is journaled in the frame 3. This latter shaft is provided, at its rear end

45 with a cam 9 which can be in the form of an elongated curved arm, as shown or of any other suitable construction. A vane 10 is extended rearwardly from the frame 3 so as to keep the wheel 5 normally in the wind.

50 The rear portion of the frame 3 is formed with a slot 10' extending upwardly and slideable within this slot is the foot 11 of a hanger 12. This hanger is slideable within an opening 13 formed in a platform 14

which is secured on and adapted to rotate 55 with frame 3.

Secured to and extending upwardly from the platform 14 are the front leg portions 15 of a figure simulating an animal. In the present instance the figure represents a 60 donkey and includes a body portion 16 pivotally connected to and extending between the upper ends of the front leg portions 15, the pivotal connection being indicated at 17.

The hind legs 18 of the figure are pivotally connected to and extend to opposite sides of the rear portion of the body 15, these leg portions being secured to a pivot member 19 adapted to rotate. A lever 20 is fixedly connected to this pivot member and is adapted 70 to swing between the sides of the body 15, there being a link 21 connecting the free end portion of this lever to the platform 14 as shown.

A strip 22 simulating the tail of the animal is pivotally connected to the body portion at 23 and the forward end of this strip is connected by a link 24 to the lever 20. Said lever 20 is also connected by a link 25 to an arm 26 extending from the pivot member 27 of the ears 28 of the figure.

Under normal conditions the figure is positioned as shown in Figure 2 with all four of the legs in contact with the platform 14, the ears 28 inclined downwardly and forwardly, and the tail 22 also hanging downwardly. The vane 10 serves to hold the wheel 5 in position where it will be actuated at all times by air currents. As the wheel 5 rotates motion will be transmitted therefrom 85 through shaft 4 and the gears 6 and 7 to the cam 9. Each time the cam 9 rotates it comes

against the foot 11 and thrusts it upwardly. This will cause the hanger 12 to thrust upwardly against the body 16 and to cause the 90 same to swing about its connection 17 with the front legs 15. As the link 21 is held to the platform 14 the lever 20 will be caused to swing downwardly relative to the body 16 and thus pull through the link 24 upon 95 the front end of the tail portion 22. At the same time lever 20 will thrust through link 25 against the arm 26 and cause the ears 28 to be lifted as shown in Figure 1. As soon as the cam 9 passes from under the foot 11 100 of hanger 12 the parts will drop by gravity to their normal positions shown in Figure 2 until the cam is again brought into place.

The action of the jointed figure in simulating the movement of an animal will of course attract the attention of passers by so that the sign thus becomes of considerable value as an advertising medium.

It will be understood that various kinds of animals can be displayed and operated by practically the same mechanism as has been described.

10. What is claimed is:

1. The combination with a structure mounted for rotation, a wind wheel carried thereby, and a vane, of a figure comprising pivotally connected members, one member of the figure being anchored to said structure, a cam actuated by the wind wheel, means operated intermittently by the cam for shifting the other members of the figure relative to said structure, and means connected to said structure and to one of the shiftable members of the figure for moving said shiftable members relative to each other during the movement of the figure relative to the structure.
- 20

2. The combination with a structure 25 mounted for rotation, a wind wheel carried thereby and a vane, of a cam actuated by the wind wheel, a figure comprising pivotally connected fixed and movable portions, the fixed portion being mounted on and anchored to the structure, a hanger pivotally connected to one of the movable portions of the figure, a guide therefor, said hanger being positioned for intermittent actuation by the cam to intermittently shift the figure 30 relative to the structure, a link pivotally connected to said structure, and lever and link connections between said link and one of the movable portions of the figure for actuating said movable portions relative to 35 each other through the shifting of the figure relative to the structure.

In testimony that we claim the foregoing as our own, we have hereto affixed our signatures.

ALONZO HALLIN PENCE.
WILLIAM ALONZO PENCE.
